MINING APPARATUS

Cornelius G. Boudette, Claremont, N. H., assignor
to Sullivan Machinery Company, a corporation
of Massachusetts

Continuation of application Serial No. 550,469,
July 13, 1931. This application April 5, 1934,
Serial No. 719,169

38 Claims. (Cl. 262—28)

This invention relates to mining apparatus and more particularly to improved adjustable kerf cutting mechanism for such an apparatus. An object of this invention is to provide an improved coal mining apparatus. Another object is to provide an improved coal mining apparatus having improved adjustable kerf cutting mechanism. A further object is to provide an improved coal mining apparatus of the wheel mounted, track guided type adapted to operate from the mine trackway and having improved adjustable kerf cutting mechanism whereby a horizontal kerf may be cut at the level of the mine bottom outside and below the level of the mine trackway. A further object is to provide an improved coal mining apparatus of the so-called combined type having improved adjustable kerf cutting mechanism adapted both for horizontal cutting and shearing. Still another object is to provide an improved adjustable kerf cutting mechanism for a mining apparatus of the aforesaid character having improved adjustable kerf cutter supporting means whereby the kerf cutter may be positioned to cut a horizontal kerf at the level of the mine bottom outside and below the level of the mine trackway and having associated therewith improved kerf cutter swinging means. Yet another object is to provide, in a mining apparatus of the aforesaid character, improved kerf cutter swinging means capable of effecting swinging of the kerf cutter in either horizontal or vertical planes in an improved manner. These and other objects and advantages of this invention will, however, herein-after more fully appear.

In the accompanying drawings there is shown, for purposes of illustration, one form which the invention may assume in practice.

In these drawings,—

Fig. 1 is a plan view of the illustrative embodiment of the improved mining apparatus.

Fig. 2 is a side elevational view of the mining apparatus shown in Fig. 1.

Fig. 3 is an enlarged plan view of the forward or cutter carrying end of the apparatus shown in Fig. 1, the top cover being removed to show the internal mechanism.

Fig. 4 is a longitudinally extending vertical sectional view taken substantially on line 4—4 of Figs. 1 and 3.

Fig. 5 is a horizontal sectional view taken substantially on line 5—5 of Fig. 4.

In this illustrative embodiment of the invention there is shown a mining machine of the same general type as that disclosed in the patent

to Morris P. Holmes, Patent No. 1,785,961, patented December 23, 1930 and having an improved adjustable kerf cutting mechanism of the same general type as that disclosed in the copending application of Morris P. Holmes, Ser. No. 415,051, filed December 18, 1929, patented October 25, 1932, No. 1,884,693, with improvements incorporated therein as hereinafter described. The mining apparatus generally comprises a truck frame 1 mounted on truck wheels 2 adapted to run along a mine trackway 3. Supported on the truck frame 1 within transverse bearing frames 4 and 5 for rotation about a longitudinally extending axis relative to the truck frame is a support or body 6 carrying the improved adjustable kerf cutting mechanism generally designated 7. Supported within the rotatable support or frame 6 and arranged with its axis alined with the support axis is a horizontal motor 8, herein preferably of the reversible electric type, having its power shaft horizontally disposed and extending longitudinally of the apparatus. This motor 8 effects drive of the truck wheel driving mechanism for propelling the apparatus along the mine trackway, and the mechanism for rotating the support 6 about its axis relative to the truck frame, in the manner clearly described in the above mentioned Holmes patents, and as these mechanisms do not specifically enter into this invention, further description of the same herein is thought unnecessary.

Now referring to the improved adjustable kerf cutting mechanism 7, it will be noted that supported on the forward end of the rotatable support 6 for rotation therewith is a cutter head 9 having pivotally mounted thereon a horizontally extending arm or extension frame 10 which in turn provides at its outer extremity a pivotal support for the kerf cutter 11, the kerf cutter being swingable by power through improved connections to be hereinafter described relative to the extension frame 10 and with the extension frame about the extension frame pivot. The kerf cutter comprises a plane cutter bar 12 having mounted on its margin, for circulation therewith, a cutter bit carrying chain 13. The driving connections between the motor 8 and the cutter chain 13 herein comprise, as shown in Fig. 4, a shaft 14 alined with and driven by the motor power shaft. Fixed to the shaft 14 is a spur pinion 15 meshing with a spur gear 16 fixed to a longitudinal shaft 17 herein arranged parallel with the shaft 14. Fixed to shaft 17 is a bevel pinion 18 meshing with a bevel gear 19 suitably journaled within the cutter head 9, and this bevel

gear meshes with a bevel gear 29 fixed to a longitudinally extending horizontal shaft 21 herein suitably journaled within a bearing bracket 22 formed on the swingable extension frame 10. 5 As shown, keyed to the shaft 21 is a spur gear 23 meshing with a spur gear 24 keyed to a horizontal shaft 25 having its axis extending radially from the axial line of the extension frame pivot and suitably journaled within the extension frame. Keyed to the forward end of the shaft 10 10 25 is a bevel pinion 26 meshing with a bevel gear 27 which is connectible by a sliding clutch 28 to a shaft 29 herein arranged with its axis coincident with the bar pivot axis and suitably journaled within the outer extremity of the swingable extension frame 10. Keyed to the shaft 29 is a chain sprocket 30 which engages and drives the cutter chain 13 in a well known manner.

The mechanism for effecting swinging of the extension frame 10 about its axis relative to the cutter head 9 comprises a shaft 31 arranged with its axis coincident with the extension frame pivot and suitably journaled within the cutter head 9, as shown in Fig. 4. The hub of the bevel gear 19 is provided with clutch teeth 32 which are connectible to the teeth of a sliding clutch member 33 splined to the shaft 31. This sliding clutch member is provided with suitable shifter mechanism including a pivoted shipper yoke 34. It will 20 25 30 thus be seen that when the clutch 33 is connected, the shaft 31 may be driven by the bevel gear 19 of the cutter chain driving mechanism. As shown in Figs. 4 and 5, fixed to the shaft 31 is a worm 35 meshing with a worm wheel 36 keyed to a horizontal shaft 37 herein arranged transversely of the cutter head and suitably journaled within the swingable extension frame 10. Journaled on the shaft 37 and connectible thereto by a multiple disc clutch 38 is a worm 39 35 40 meshing with a worm wheel 40. This worm wheel is journaled on a shaft 41 likewise suitably journaled within the extension frame 10 and this worm wheel 40 is connectible to the shaft 41 by a sliding clutch 42. The shaft 41 drives a spur pinion 43 meshing with the teeth of a large internal gear 44 journaled within the cutter head. Also rotatably mounted on the shaft 37 and connectible thereto by a multiple disc clutch 45 is a worm 46 similar to the worm 39, but having oppositely inclined teeth, meshing with a worm wheel 47 journaled on a shaft 48 in turn suitably journaled within the swingable extension frame 10 and the worm wheel 47 is connectible with the shaft 48 by a sliding clutch 49. Driven by the shaft 48 is a spur pinion 50 likewise meshing with the teeth of the internal gear 44. As shown in Fig. 5, the clutches 38 and 45 are provided with suitable shipper mechanism including pivoted shipper yokes 51 and 52 and an operating handle 53, while the sliding clutches 42 and 49 55 60 65 70 75 are provided with suitable shipper yokes 54 and 55 respectively having an operating handle 56. It will thus be seen that upon suitable application of the disc clutches 38, 45 and connection of clutches 42 and 49, the internal gear 44 may be driven in one direction or the other. It is accordingly evident that when the internal gear 44 is held against rotation relative to the extension frame 10, the extension frame may be swung relative to the cutter head 9 in one direction or the other, and that when the disc clutches 38 and 45 are released and one of the clutches 42, 49 is connected, the extension frame is locked automatically by the self locking worm gearing of the swinging mechanism. When the clutches 38, 45 and clutches 42, 49 are all released, the extension frame is free to swing relative to the cutter head. As shown, the extension frame 10 is journaled for swinging movement within sleeve bearings 57 and 58 carried by the cutter head frame, and the internal gear 44 is rotatably mounted in bearing sleeves 59 carried by the extension frame and held in position by a retaining ring 60 bolted to the cutter head frame. The means for holding the internal gear 44 against rotation relative to the cutter head frame may assume various forms, but in this instance comprises, as shown in Fig. 4, a spring pressed plunger lock 61 reciprocably mounted in a bore 62 formed in a boss integral with the retaining ring 60. The plunger lock 61 is adapted to enter apertures 63 formed in bosses formed around the periphery of a member 64 bolted to the internal gear 44. The lock 61 is held in locking position by a coiled spring 65 acting thereon, and is provided with a handle 66 for the release of the same. A projection 67 is formed on the lock 61, and when the lock is pulled outwardly and then turned, the projection holds the lock in its released position. It will thus be seen that as the bore 62 is in registry with one of the apertures 63 the internal gear 44 may be locked positively to the cutter head frame, and when the lock is released may rotate freely relative to the cutter head frame.

Now referring to the improved mechanism for swinging the cutter bar 12 about its pivot relative to the extension frame 10, it will be noted that the member 64 secured to the internal gear 44 forms a bearing support for one end of the shaft 31 and has clutch teeth 68 connectible by a sliding clutch 69 to clutch teeth 70 formed on the hub of a sprocket 71 rotatably supported on the shaft 31. The sliding clutch 69 is provided with suitable shifter mechanism including a pivoted shipper yoke 72 and an operating handle 73. As shown in Fig. 4, the sprocket 71 is connected by an endless chain 74 to a sprocket 75, herein formed integral with a cylindrical bearing support 76 for the cutter bar 12. The bearing mounting 76 for the cutter bar is journaled in a bearing sleeve 77 carried by the outer extremity of the extension frame 10, as illustrated. It will thus be seen that when the lock 61 is in its released position and the internal gear 44 is free to rotate relative to the extension frame 10 and the clutch 69 is connected, the sprocket 71 may be driven by the internal gear 44 while the extension frame 10 remains stationary as regards swinging movement relative to the cutter head, and as a result, the cutter bar is swung about its pivot relative to the extension frame through the chain and sprocket connection 74, 75. It will also be evident that when the clutch 69 is released, and the internal gear 44 is held against rotation relative to the cutter head frame, the extension frame may be swung about its pivot relative to the cutter head while the cutter bar is freely swingable relative to the extension frame. If desired, however, the cutter bar may be held against swinging movement relative to the extension frame during swinging of the latter about its pivot, by any suitable means, for instance by a spring pressed plunger lock 78 similar to the lock 61 and having a release handle 79 and adapted to enter apertures 80 formed in a flange 81 formed integral with the bearing mounting 76 for the kerf cutter. The lock 78 is held released in the same manner as the lock 61, by a projection 82. The extension frame 10 is held against swinging movement relative to the cutter head during swinging of the cutter bar 75

about its pivot by any suitable means, herein a locking pin 83 insertible within registering apertures 84 and 85 formed in the cutter head 9 and extension frame 10, respectively. As shown in Fig. 1, the cutter head is provided in appropriate locations with a plurality of apertures 84 to enable locking of the extension frame in a plurality of angular positions relative to the cutter head. It will thus be seen that the cutter bar may swing freely relative to the extension frame or may be positively locked against swinging movement relative thereto by the lock 78, and that the extension frame may be locked to the cutter head or released at will.

As the mode of operation of the mining apparatus disclosed herein is clearly described in the first above mentioned Holmes patent, and as the method of operation of the kerf cutting mechanism and the mode of adjustment thereof is clearly described in the second mentioned Holmes patent, a further description of the mode of operation of the improved apparatus is thought unnecessary other than to state that the extension frame 10 may be swung relative to the cutter head 9 and the cutter bar 11 may be swung relative to the extension frame at the will of the operator, that the support 6 may be rotated within its bearings relative to the truck frame to position the cutter head 9 into either a horizontal or a shearing position and that the cutter bar may be swung about its pivot to effect either a horizontal or a shearing cut. These and other uses and advantages of the improved adjustable kerf cutting mechanism will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

This is a continuation of my application Serial No. 550,469 filed July 13, 1931, Mining apparatus.

What I claim as new and desire to secure by Letters Patent is:

1. In a mining apparatus, a portable base and kerf cutting mechanism mounted on said base including a horizontal arm pivotally mounted on the base for swing about a vertical axis adjacent its rearward end, a kerf cutter pivotally mounted on the outer extremity of said arm to swing about an axis parallel with the arm pivot axis, and mechanism for alternatively swinging said arm relative to said base and said kerf cutter relative to said arm and including gearing common to the swinging of said arm and kerf cutter and arranged on said arm at the rear of the arm pivot and swingable with said arm during arm swing.

2. In a mining apparatus, a portable base and kerf cutting mechanism mounted on said base including a horizontal arm pivotally mounted on said base to swing about a vertical axis located in advance of said base, a kerf cutter pivotally mounted on the outer extremity of said arm, and mechanism for swinging said arm and kerf cutter about their respective pivots including motor operated kerf cutter and arm swinging devices carried by the rearward extremity of said arm at the rear of the arm pivot axis.

3. In a mining apparatus, a portable base and kerf cutting mechanism mounted on said base including a horizontal arm pivotally mounted on said base to swing about a vertical axis lo-

cated in advance of said base, a kerf cutter pivotally mounted on the outer extremity of said arm, and mechanism for swinging said kerf cutter relative to said arm including motor operated devices carried by the rearward extremity of said arm, said devices including a reverse mechanism for effecting swinging of said kerf cutter in either of opposite directions without reversing said kerf cutter.

4. In a mining apparatus, a portable base and kerf cutting mechanism mounted on said base including a horizontal arm pivotally mounted on said base to swing about a vertical axis located in advance of said base, a kerf cutter pivotally mounted on the outer extremity of said arm, and mechanism for swinging said arm about its pivot relative to said base and for swinging said kerf cutter relative to said arm including a common kerf cutter swinging and arm swinging gearing carried by the rearward extremity of said arm.

5. In a mining apparatus, a portable base and kerf cutting mechanism mounted on said base including a horizontal arm pivotally mounted on said base to swing about a vertical axis located in advance of said base, a kerf cutter pivotally mounted on the outer extremity of said arm, and mechanism for alternatively swinging said arm and kerf cutter and each in either of opposite directions, including a common kerf cutter and arm swinging reverse gearing carried by the rearward extremity of said arm.

6. In a mining apparatus, a portable base and kerf cutting mechanism mounted on said base including an arm pivotally mounted on said base to swing horizontally relative thereto, a kerf cutter pivotally mounted on the outer extremity of said arm, and mechanism including common swing gearing for swinging said kerf cutter relative to said arm and said arm relative to said base and including locking devices for holding said arm against swinging movement relative to said base to effect swinging of said kerf cutter.

7. In a mining apparatus, a portable base and kerf cutting mechanism mounted on said base including an arm pivotally mounted on said base to swing horizontally relative thereto, a kerf cutter pivotally mounted on the outer extremity of said arm, and mechanism including common swing gearing for swinging said kerf cutter relative to said arm and said arm relative to said base and including locking devices for holding said arm against swinging movement relative to said base during swinging of said kerf cutter including a releasable lock for holding said arm in different angular positions relative to said base to effect kerf cutter swing.

8. In a mining apparatus, a portable base, a support thereon having its outer extremity overhanging said base, and kerf cutting mechanism mounted on said base including a horizontal arm pivotally mounted on the outer overhanging extremity of said support, a kerf cutter pivotally mounted on the outer extremity of said arm, and mechanism for swinging said kerf cutter relative to said arm including a driven element secured to said kerf cutter, a driving element at the rear extremity of said arm, a driving connection extending between and connecting said driving and driven elements, and means for locking said driving element to said arm to effect arm swing, said locking means being released during kerf cutter swing.

9. In a mining apparatus, a portable base, an

- 4 extension frame pivotally mounted on the forward end of said base for horizontal swinging movement relative thereto about a vertical axis located in advance of said base, a kerf cutter 5 pivotally mounted on the outer extremity of said extension frame for swinging movement relative thereto, and mechanism for swinging said kerf cutter relative to said extension frame including kerf cutter swinging gearing carried 10 within the rearward portion of the said extension frame and swingable bodily with the latter about the frame axis during frame swing.
10. In a mining apparatus, a portable base, an extension frame pivotally mounted on the forward end of said base for horizontal swinging movement relative thereto, a kerf cutter pivotally mounted on the outer extremity of said extension frame for swinging movement relative thereto, mechanism for swinging said kerf cutter relative 15 to said extension frame including kerf cutter swinging gearing carried within the rearward portion of the said extension frame at the rear of the frame pivot and swingable bodily with the frame about the pivot thereof during swinging 20 of said frame, and a driving element for said gearing arranged with its axis alined with the extension frame pivot axis.
11. In a mining apparatus, a portable base, an elongated extension frame pivotally mounted on the forward end of said base for horizontal swinging movement relative thereto, a kerf cutter pivotally mounted on the outer extremity of said extension frame for swinging movement relative thereto about an axis parallel with the extension frame pivot, and mechanism for swinging 35 said kerf cutter about its pivot relative to said extension frame including clutch controlled kerf cutter swinging mechanism carried within the rearward portion of said extension frame and including a transverse shaft journaled within the rearward portion of said extension frame.
12. In a mining apparatus, a portable base, an extension frame pivotally mounted on the forward end of said base for horizontal swinging movement relative thereto, a kerf cutter pivotally 40 mounted on the outer extremity of said extension frame for swinging movement relative thereto, mechanism for swinging said kerf cutter about its pivot relative to said extension frame including 45 clutch controlled kerf cutter swinging mechanism carried within the rearward portion of said extension frame and including a transverse shaft journaled within the rearward portion of said extension frame, and a shaft alined with the extension frame pivot axis and operatively connected to said transverse shaft.
13. In a mining apparatus, a portable base, an extension frame pivotally mounted on the forward end of said base for horizontal swinging movement relative thereto, a kerf cutter pivotally 50 mounted on the outer extremity of said extension frame for swinging movement relative thereto, and mechanism for swinging said kerf cutter about its pivot including clutch controlled 55 kerf cutter swinging mechanism carried within the rearward portion of said extension frame and including a transverse shaft journaled within the rearward portion of said extension frame, a shaft alined with the extension frame pivot axis and worm gearing connecting said shafts in driving relation.
14. In a mining apparatus, a portable base, an extension frame pivotally mounted on the forward end of said base for horizontal swinging movement relative thereto, a kerf cutter pivotally 60
- 65 mounted on the outer extremity of said extension frame for swinging movement relative thereto, mechanism for swinging said kerf cutter about its pivot including clutch controlled kerf cutter swinging mechanism carried within the rearward portion of said extension frame and including a transverse shaft journaled within the rearward portion of said extension frame, a shaft alined with the extension frame pivot axis and operatively connected to said transverse shaft for drive thereby, and gears coaxial with said transverse shaft, one to effect kerf cutter swing in one direction and the other in the reverse direction.
15. In a mining apparatus, a portable base, an extension frame pivotally mounted on the forward end of said base for horizontal swinging movement relative thereto, a kerf cutter pivotally mounted on the outer extremity of said extension frame for swinging movement relative thereto, mechanism for swinging said kerf cutter about its pivot including clutch controlled kerf cutter swinging mechanism carried within the rearward portion of said extension frame and including a transverse shaft journaled within the rearward portion of said extension frame, a shaft alined with the extension frame pivot axis and operatively connected to said transverse shaft for drive thereby, gears coaxial with said transverse shaft, one to effect kerf cutter swing in one direction and the other in the reverse direction, and clutches for selectively connecting said coaxial gears in driving relation with said transverse shaft.
16. In a mining apparatus, a portable base, a support mounted on the forward end of said base for rotation relative thereto about a longitudinal axis, an arm pivotally mounted on said rotatable support to swing relative thereto and a kerf cutter pivotally mounted on the outer extremity of said arm to swing relative to said arm, and motor operated devices for swinging said arm relative to said rotatable support and said kerf cutter relative to said arm, said arm swinging and kerf cutter swinging devices being alternatively operable and including gearing effective to effect either swing arranged at the rear of the arm pivot and swingable bodily with said arm about the arm pivot during arm swing.
17. In a mining apparatus, a portable base, a support mounted on the forward end of said base for rotation relative thereto about a longitudinal axis, an arm pivotally mounted on said rotatable support and a kerf cutter pivotally mounted on the outer extremity of said arm, and motor operated devices for swinging said arm relative to said rotatable support and said kerf cutter relative to said arm and including kerf cutter swinging gearing carried within the rear portion of said arm adjacent to and at the rear of said arm pivot and swingable bodily with the arm about the arm pivot during arm swing.
18. In a mining apparatus, a portable base and kerf cutting mechanism mounted on said base including a horizontal arm pivotally mounted on said base, a kerf cutter pivotally mounted on the outer extremity of said arm, and mechanism for alternatively swinging said arm relative to said base and said kerf cutter relative to said arm including a gear journaled on said arm and rotatable relative thereto during and to effect kerf cutter swings, and means for holding said gear stationary relative to said base to effect swinging movement of said arm.
19. In a mining apparatus, a portable base and kerf cutting mechanism mounted on said base

- including a horizontal arm pivotally mounted on said base, a kerf cutter pivotally mounted on the outer extremity of said arm, and mechanism for alternatively swinging said arm relative to said base and said kerf cutter relative to said arm including a gear journaled on said arm and rotatable relative thereto during and to effect kerf cutter swing, and a releasable lock carried by said base and connectible to said gear for holding said gear stationary relative to said base to effect arm swing.
20. In a mining apparatus, a portable base and kerf cutting mechanism mounted on said base including a horizontal arm pivotally mounted on said base, a kerf cutter pivotally mounted on the outer extremity of said arm, and mechanism for alternatively swinging said arm relative to said base and said kerf cutter relative to said arm including a gear journaled on said arm and rotatable relative thereto during and to effect kerf cutter swing, means for holding said gear stationary relative to said base to effect swinging movement of said arm, and means for rotating said gear in either of opposite directions without reversing said kerf cutter.
21. In a mining apparatus, a wheel supported frame adapted to run along a mine trackway and overhanging in advance of the front support wheels, an arm pivotally mounted on the overhanging end of said frame to swing horizontally across the forward end of said frame, a kerf cutter pivotally mounted on the outer extremity of said arm to swing horizontally relative thereto about an axis parallel with the arm axis, and mechanism including gearing carried by said arm and common to the swinging of said arm and of said kerf cutter respectively, for swinging said arm and kerf cutter about their respective pivots, and means for rendering said gearing inoperative to effect arm swinging during the swinging by said gearing of said kerf cutter.
22. In a mining apparatus, a wheel supported frame adapted to run along a mine trackway and overhanging in advance of the front support wheels, an arm pivotally mounted on the overhanging end of said frame to swing horizontally across the forward end of said frame, a kerf cutter pivotally mounted on the outer extremity of said arm to swing horizontally relative thereto about an axis parallel with the arm axis, and mechanism including reverse gearing carried by said arm and common to the swinging of said arm and kerf cutter on their respective axes for swinging said arm and kerf cutter in opposite directions about their respective pivots, said reverse gearing being swingable bodily about the arm pivot during arm swing.
23. In a mining apparatus, a portable base, an arm pivotally mounted on said base to swing horizontally relative thereto about a vertical axis located in advance of said base, a kerf cutter pivotally mounted on the outer extremity of said arm to swing relative thereto about a parallel axis, means including common swing gearing for swinging said arm relative to said base and for swinging said kerf cutter relative to said arm, either while the other is stationary, and releasable locking devices for locking said arm against swinging movement relative to said base during swinging of the kerf cutter and for locking said kerf cutter against swinging movement relative to said arm during arm swing.
24. In a mining apparatus, a portable base, an arm pivotally mounted on said base to swing horizontally relative thereto about a vertical axis, a kerf cutter pivotally mounted on the outer extremity of said arm to swing relative thereto about a parallel axis, and motor operated devices for swinging said arm to swing relative thereto about a vertical axis, including a rotatable kerf cutter swinging element arranged with its axis coincident with the arm pivot axis, and means for locking said element against rotation during arm swing.
25. In a mining apparatus, a portable base, an arm pivotally mounted on said base to swing horizontally relative thereto about a vertical axis, a kerf cutter pivotally mounted on the outer extremity of said arm to swing relative thereto about a parallel axis, and motor operated devices for swinging said arm relative to said base and for swinging said kerf cutter relative to said arm including a rotatable kerf cutter swinging element arranged with its axis coincident with the arm pivot axis, and means for locking said element against rotation during arm swing, and clutch devices for connecting said kerf cutter to said swinging element or releasing the same therefrom at will.
26. In a mining apparatus, a portable base, an arm pivotally mounted on said base to swing horizontally relative thereto about a vertical axis, a kerf cutter pivotally mounted on the outer extremity of said arm to swing relative thereto about a parallel axis, motor operated devices for swinging said arm relative to said base and for swinging said kerf cutter relative to said arm including a rotatable kerf cutter swinging element arranged with its axis coincident with the arm pivot axis, means for locking said element against rotation during arm swing, clutch devices for connecting said kerf cutter to said swinging element or releasing the same therefrom at will, and means releasable at will for locking said kerf cutter against swinging movement relative to said arm.
27. In a mining apparatus, a portable base, an arm mounted on said base to swing horizontally relative thereto about a vertical axis located in advance of said base, a kerf cutter pivotally mounted on the outer extremity of said arm to swing relative thereto about a parallel axis, and motor operated devices for swinging said arm about its pivot relative to said base and for swinging said kerf cutter relative to said arm including a gearing common to both swings and carried by said arm at the rear of the arm pivot axis and swingable bodily with the arm about the arm pivot during arm swing, said gearing being operable to effect alternatively swinging of said arm and swinging of said kerf cutter each about its respective axis of swing.
28. In a mining apparatus, a portable base, an arm mounted on said base to swing horizontally relative thereto about a vertical axis located in advance of said base, a kerf cutter pivotally mounted on the outer extremity of said arm to swing relative thereto about a parallel axis, and motor operated devices for swinging said arm about its pivot relative to said base and for swinging said kerf cutter relative to said arm including a reversible gearing carried by said arm at the rear of the arm pivot axis and swingable bodily with the arm about the arm pivot during arm swing, said gearing being operable to effect alternatively swinging of said arm and swinging of said kerf cutter, each about its own axis of swing, in opposite directions.
29. In a mining apparatus, a frame, an arm pivotally mounted on said frame to swing relative

- thereto, a kerf cutter pivotally mounted on the outer extremity of said arm to swing relative thereto about an axis parallel to the arm axis, and mechanism for swinging said arm relative to said frame and said kerf cutter relative to said arm including a driving member rotatable about an axis coincident with the arm pivot axis, means for connecting said kerf cutter to said member for swing thereby, said means being released during swinging of said arm, and means for locking said member against rotation during arm swing.
30. In a mining apparatus, a frame, an arm pivotally mounted on said frame to swing relative thereto, a kerf cutter pivotally mounted on the outer extremity of said arm to swing relative thereto about an axis parallel to the arm axis, and mechanism for swinging said arm relative to said frame and said kerf cutter relative to said arm including a driving element rotatable about an axis coincident with the arm pivot axis, means for connecting said kerf cutter to said element for swing thereby, said means being released during swinging of said arm, and means for locking said element against rotation during arm swing, said element being freely rotatable relative to said arm during swing of the kerf cutter, and means for locking said arm against swinging movement relative to said frame during kerf cutter swing.
31. In a mining apparatus, a frame, an arm pivotally mounted on said frame to swing relative thereto, a kerf cutter pivotally mounted on the outer extremity of said arm to swing relative thereto about an axis parallel to the arm axis, and mechanism for swinging said arm relative to said frame and said kerf cutter relative to said arm including a driving element rotatable about an axis coincident with the arm pivot axis, means for connecting said kerf cutter to said element for swing thereby, said means being released during swinging of said arm, means for locking said element against rotation during arm swing, and reverse gearing carried by said arm and swingable therewith about the arm axis for effecting rotation of said element in opposite directions.
32. In a mining apparatus, a frame, an arm pivotally mounted on said frame to swing relative thereto, a kerf cutter pivotally mounted on the outer extremity of said arm to swing relative thereto about an axis parallel to the arm axis, and mechanism for swinging said arm relative to said frame and said kerf cutter relative to said arm including a driving element rotatable about an axis coincident with the arm pivot axis, means for connecting said kerf cutter to said element for swing thereby, said means being released during swinging of said arm, means for locking said element against rotation during arm swing, and gearing carried by said arm and swingable therewith about the arm axis for effecting rotation of said element.
33. In a mining apparatus, a frame, an arm pivotally mounted on said frame to swing relative thereto, a kerf cutter pivotally mounted on the outer extremity of said arm to swing relative thereto about an axis parallel to the arm axis, and mechanism for swinging said arm relative to said frame and said kerf cutter relative to said arm including a driving element rotatable about an axis coincident with the arm pivot axis, means for connecting said kerf cutter to said element for swing thereby, said means being released during swinging of said arm, means for locking said element against rotation during arm swing, and reversible gearing carried by said arm and swingable therewith about the arm axis for effecting rotation of said element in opposite directions.
34. In a mining apparatus, a wheel supported base adapted to run along a mine trackway, and kerf cutting mechanism mounted on said base including a horizontal arm pivotally mounted on the base and swingable horizontally, a kerf cutter pivotally mounted on the outer extremity of said arm to swing about an axis parallel with the arm pivot axis, said arm being swingable about its pivot relative to said base to position the kerf cutter pivot outside the trackway at either side of the trackway, and mechanism for alternatively swinging said arm relative to said base and said kerf cutter relative to said arm and including gearing common to the swinging of said arm and kerf cutter and effective to cause alternative swingings thereof and arranged on said arm at the rear of the arm pivot and swingable with said arm during arm swing.
35. In a mining apparatus, a wheel supported base adapted to run along a mine trackway, and kerf cutting mechanism mounted on said base including a horizontal arm pivotally mounted on said base about a vertical axis located in advance of said base in front of the front wheels thereof, a kerf cutter pivotally mounted on the outer extremity of said arm, said arm being swingable horizontally relative to said base to position the kerf cutter pivot outside the trackway at either side of the trackway, and mechanism for swinging said arm relative to said base and said kerf cutter relative to said arm including motor operated kerf cutter and arm swinging devices carried by the rearward extremity of said arm at the rear of the arm pivot axis and effective to swing either said arm or said kerf cutter.
36. In a mining apparatus, a wheel supported base adapted to run along a mine trackway, and kerf cutting mechanism mounted on said base including a horizontal arm pivotally mounted on said base to swing about a vertical axis located in advance of said base in front of the front wheels thereof, a kerf cutter pivotally mounted on the outer extremity of said arm, said arm being swingable horizontally relative to said base to position the kerf cutter pivot outside the trackway at either side of the trackway, and mechanism for swinging said arm relative to said base and said kerf cutter relative to said arm including motor operated kerf cutter and arm swinging devices carried by the rearward extremity of said arm at the rear of the arm pivot axis, said devices including a reverse mechanism for effecting swinging of either said kerf cutter or said arm in either of opposite directions about its respective pivot without reversing said kerf cutter.
37. In a mining apparatus, a wheel supported base adapted to run along a mine trackway, and kerf cutting mechanism mounted on said base including a horizontal arm pivotally mounted on said base about a vertical axis located in advance of said base in front of the front wheels thereof, a kerf cutter pivotally mounted on the outer extremity of said arm, said arm being swingable horizontally relative to said base to position the kerf cutter pivot outside the trackway at either side of the trackway, and mechanism for swinging said arm about its pivot relative to said base and for swinging said kerf cutter relative to said arm including a common kerf cutter swinging and arm swinging gearing carried by the rearward extremity of said arm and effective selectively to cause either arm or cutter swing.
38. In a mining apparatus, a wheel supported

base adapted to run along a mine trackway, an arm pivotally mounted on the forward end of said base to swing horizontally relative thereto about a vertical axis located in advance of the front wheels thereof, a kerf cutter pivotally mounted on the outer extremity of said arm to swing relative thereto about an axis parallel with the arm pivot axis, said arm being swingable horizontally relative to said base to position the kerf cutter pivot outside the trackway at either

side of the trackway and to move the kerf cutter in an arcuate path across the end of the trackway, and common motor operated devices for swinging said arm and kerf cutter about their respective pivots independently of each other and including means for holding said arm against swinging movement about its pivot during swinging of said kerf cutter.

CORNELIUS G. BOUDETTE. 10
